ELASTIC WAVE TELEVISION SYSTEM

Alexander McLean Nicolson, New York, N. Y., assignor to Communication Patents, Inc., New York, N. Y., a corporation of Delaware

Application July 1, 1932, Serial No. 620,380

15 Claims. (Cl. 178—6)

This invention relates to electrical transmission systems, and particularly to such systems adaptable for the initiation and reception of electrical impulses characterized by the light and shade densities of objects or images thereof.

An object of the invention is to initiate electrical impulses characterized by the light and shade densities of objects and transform such impulses into varying light intensities proportional thereto.

Another object of the invention is to obtain greater efficiency of reproduction of light images and to retain any desired image indefinitely.

A further object of the invention is to produce, with a given amount of light, images having a brilliancy many times greater than that obtainable at present.

A still further object of the invention is to produce a commutating effect without the use of any mechanical moving parts except that of wave motion within a metallic medium.

The present type of television transmission and reproduction of images has been based on the principle of scanning or exploring. This principle in brief, is the obtaining of electrical currents proportional to the light and shade densities of unit areas of objects in a serial order each unit area of the object or image providing a certain current amplitude or frequency which represents the light intensity value upon that unit area. It is necessary with such a system to produce all the unit areas within a time interval which permits the eye to retain the first light impulse during the entire period of scanning. Furthermore, to obtain the illusion of motion of objects, it is necessary to present each full image at the rate of at least ten images per second.

Basing further conclusions on the present standard speed of transmission which is sixty lines at twenty repetitions per second, each unit area is, therefore, presented to the eye during 1/72,000 of a second. With sixty lines there exists approximately 3600 unit areas each of which is scanned and presented to the eye at this rate. It is obvious, therefore, that an intense light must be employed to obtain sufficient illumination for a practical sized image. If it is possible, however, to maintain the illumination of a unit area for a period of a twentieth of a second or longer, instead of the present 1/72,000 of a second it is quite obvious that the intensity of the image will be multiplied many fold without increasing the intensity of the light source itself.

The above feature is presented in the following disclosure together with a commutator operating

without mechanical moving parts except the movement of certain mediums caused by the transmission of waves therethrough. It is well known mechanically that the speed of transverse waves along elastic mediums such as a wire is 60 determinable by the tension in the wire and the nature of the material making up the wire. These waves may be propagated at a rate exceeding 2000 feet per second. In the same type of medium a longitudinal wave may be propagated at 65 even greater speeds. In the present disclosure one or both modes of vibration are utilized, some modifications employing the heterodyne principle well known in the electrical art in which two elastic frequencies produce a beat note to which 70 a mechanical element is resonant. This elastic wave commutating system is being claimed in a divisional application Serial No. 687,950, filed September 2, 1933.

To obtain the persistency effect, that is, the 75 retention of the light on a unit area for a period of approximately 1/20th of a second, a plurality of shutters or gates representing each unit area is adjusted by the incoming current impulses to pass a quantity of light proportional to the strength 80 of the incoming impulse. This gate or shutter adjustment is maintained during the time period required to adjust the other shutters and continues in its original adjustment until such instant as the light intensity changes for that unit area. A 85 system is thus disclosed in which only the shutters representing unit areas varying in intensity are operated thereby providing, in effect, a constant image. An oscillator of the periodic type provides the timing impulses for the shutters which when 90 disconnected permits the maintaining of any image present at the instant of disconnection.

The invention may be more fully understood by reference to the following detailed description read in conjunction with the accompanying drawing in which:

Fig. 1 is a diagrammatic view of a receiver.

Fig. 2 is an elevational view of the persistent screen employed in the system.

Figs. 3, 4, 5, and 6 are detailed views of the 100 shutter employed in the screen of Fig. 2.

Figs. 7 and 8 are views of a heterodyne type of shutter screen; and,

Figs. 9 and 10 are modifications of elastic wave transmitters for operating the screen of Fig. 2. 105

Referring specifically to Fig. 1 which is illustrating a receiving system, an antenna 5 or wire terminal 6 may impress on a receiver 7 incoming currents characterized by the light and shade densities of unit areas scanned at a distant point. 110

The image may be scanned in any well known manner such as by the spiral aperture disk method, cathode ray or arc scanner, the latter being shown in my U. S. Patent No. 1,863,278, of June 5 14, 1932.

The output of the receiver 7 is impressed upon a solenoidal type of field represented by a single turn 8, this solenoid surrounding a gate or shutter type screen 10. The screen is actuated by an 10 oscillator 11. A source 13 energized from a supply 15 14 provides constant intensity light which is projected upon the screen 10 through a lens 15 and so focussed by the aid of multiple lens 17 as to be properly projected upon a screen 16 to any 15 desired size, the lens 17 eliminating the shadow of the shutter supports. A lattice frame 18 covers the spaces between shutters.

Referring now to Fig. 2 in which the screen 10 is shown in more detail, a frame is composed of two 20 massive sections 20 and 21 with smaller sections 22 and 23. There is strung between the sections 23 and 21 a plurality of wires 25 of a gauge in accordance with the size of the screen used. These wires are adjustably attached to the sections 25 23 and pass through section 21 to tightening nuts 26. The section 21 is of a composite type in that it is composed of layers of wave absorbing material, that is, the first layer may be of cork, the second of fibre, and the third of harder substance, such as rubber or bakelite and so on to the back section which may be of steel to obtain the necessary support for tensioning the wires.

Perpendicular to, and adjacent wires 25, and several gauges larger, is a drive wire 28 which is connected to the wires 25 through vertical projections 29. The wire 28 may be attached to an absorbing section similar to section 21. The projections 29 are a part of the wires 25, that is, the wires 25 may be looped at points 30 and connected to the frame section 23 by shorter sections 31, while the upper points of the projections are attached to the wire 28. It is obvious from this construction that a transverse wave in the wire 28 in the plane of the screen will produce a similar wave in the wires 25 in the plane of the screen but with its direction of motion shifted 90°. Mounted upon the wires 25 are a plurality of metallic gate or shutter sections 33 which will be described and shown in more detail later. The wire 28 is activated by means of a relay 34 supplied from the oscillator 11 of a type which preferably produces a peaked wave form of only a half cycle at definite intervals. The field winding 8 is shown in the form of a single coil and completely surrounds the screen 10 to produce therein a uniform magnetic field. The receiver 7, antenna 5, and wire terminal 6 are shown as in Fig. 1.

In Fig. 3 one of the wires 25 has shown mounted thereon a row of metallic shutters 33 which are strung adjacent one another so that their edges just clear one another as closely as possible. The lattice screen 18 of Fig. 1 is so placed behind the shutter as to obscure light which would ordinarily be admitted between the joints. Wire 25 is shown looping at the point 30 where it is joined to the short section 31 for tensioning to the support 23, while the vertical section of the wire 29 is connected to the wire 28 which in turn is connected to the armature of the relay 34.

Cross-sectional views of the wire 25 and the shutters 33 are shown in Figs. 4 and 5. In these views it is evident that the wires 25 do not have a circular cross section but are polygonal and surrounded by slightly larger polygonal sleeve sections to which the gates 33 are attached. This

construction is especially advantageous inasmuch as it allows the shutter 33 to remain in a fixed position when once adjusted until it is again adjusted either to its neutral position or a new position. In Fig. 6 another construction of shutter 33 is shown mounted upon the wire 25 in which the polygonal sleeve is replaced by a wire coiled about the wire 25 to form a support for the gate 33. This wire may be held in its adjusted position by friction.

Before continuing the description of the other modifications of this system, the operation of the above described embodiment will be given. The oscillator 11 produces, as stated above, an output wave which is peaked and intermittent to the extent that it produces in the wire 28 a transverse wave with a definite loop which will travel along the wire 28 at a definite speed, the proper speed being that of the speed in the transverse wires 25 divided by the number of wires. In other words, the wave in wire 28 will travel the distance between wires 25 in the same length of time that it takes a transverse wave initiated in wires 25 to travel the length of one of these wires. The waves in the wires 25 will be initiated in chronological order with the result that each gate will be released from the wire 25 in a serial order as the wave passes therealong, each shutter floating for an instant. The oscillator 11 is so coordinated with the incoming signals that the proper shutter is loosened at the time the desired impulse is impressed on the field so that the shutter will be magnetically moved either forward or backward to admit light from the source 13.

For instance, where a certain unit area of a picture is represented by the maximum light intensity, a strong impulse will strengthen the field to adjust the shutter to its maximum opening when loosened by the transverse wave from the oscillator 11. This impulse will increase the field at the proper time, which is the time the particular shutter is loosened upon its wire. When the transverse wave has passed the shutter will settle in the position to which it was adjusted by the field and remain there until the wire is activated by another transverse wave in the wire, thus permitting the eye to see light in that particular unit area during the time the other shutters are being adjusted. If on the second activation this particular unit area has changed in light intensity to zero at the transmitter then the shutter will return to its normal position by the action of gravity. It is to be understood that a constant field supplementing the action of gravity may be employed. However, should the unit area have a lesser degree of intensity than the prior adjustment, then a new adjustment will be made by the lesser field strength. As a wave passes down the vertical wire 28 each wire will be activated in turn and commutation is obtained without the use of rotating or oscillating mediums of large proportions. The waves when they reach the section 21 will be absorbed, eliminating standing waves in the wire.

It is to be noted that the field strength is so proportioned that the shutters cannot be moved thereby except when they have been loosened by the elastic waves in the supporting wires. The strength of an auxiliary field, when used to aid gravity, is also insufficient to move the shutters when at rest. This is especially desirable inasmuch as it permits the retention of any particular scene being transmitted by simply disconnecting the oscillator 11 from the screen. The last image will remain on the screen indefinitely.

since each shutter remains in its last adjustment. The scene can be reproduced at any later time by the projection of a light through the screen 10.

When using this system as a transmitter the receiver 7 will be replaced by an oscillator which opens and closes each shutter as each shutter is loosened by the elastic waves in the wires supporting them.

Referring now to the modifications in Figs. 7 and 8, a cross wire arrangement having vertical wires 40 and horizontal wires 41 which may be mounted similar to those in Fig. 2 is shown attached to driving mediums 43 and 44 respectively. These sets of wires lie in two planes adjacent one to another but not contacting. Abutting the driving wire 43 is a motor crystal element 45, while transversely placed with respect to driving wire 44, is a motor crystal 46. The crystal 45 is connected to an oscillator 48 which also supplies an harmonic generator 49 the output of the latter being impressed upon the crystal 46. By this arrangement, no waves introduced in one set of wires are transmitted to the other directly through the wires. The oscillator 48 furnishes to the crystal 45 an electrical wave of super-audible frequency while the harmonic generator 49 supplies the generator 46 with a higher frequency. The wave produced in the driving wire 44 is transverse while that in the driving wire 43 is longitudinal but these waves beat together to produce the necessary beat frequency desired, which may be within the audible range.

Referring now to Fig. 8 a wire 40 and a wire 41 of Fig. 7 is shown having mounted thereon shutters 51 and 52 respectively, the shutters being interconnected by means of a coil spring 53. This is a unit area section and is mounted at each intersection of the wires 40 and 41. The spring 53 and the gates 51 and 52 provide a connection between the frequencies in the wires and is so constructed that the assembly is resonant to the beat frequency. When the two high frequencies arrive at the hinges of shutters simultaneously the beat frequency vibrates the assembly and loosens the shutters in the manner of that in Fig. 2. There is produced, therefore, by this construction, a commutating arrangement on the heterodyne principle in which a longitudinal wave is sent along a driving wave initiating either longitudinal or transverse waves in the wires in one plane, while another frequency is sent along the wires in the other plane, neither frequency of which has any effect upon loosening the shutters except when both frequencies are present simultaneously to form the beat vibration. A model of this type of shutter provided an opening that increased along two sides in a perfect square. It is to be understood that the gates or some parts thereof are of magnetic material so as to be affected by the field as in Fig. 2. It is also to be understood that a single gate structure may be operated on the heterodyne principle by the use of parallel wires cooperating with wires 25 in Fig. 2 or cross wires as in Fig. 7 with interconnecting links.

Referring now to Figs. 9 and 10 two means of obtaining travelling waves without employing absorbing means is illustrated. In Fig. 9 a vertical driving wire 60 is connected to horizontal screen wires 61 at points 62. The wire 60 is driven from a crystal 63 to initiate therein a transverse wave, this wave passing the last wire and continuing on to a fixed support 64 from which it is reflected. However, the length of the section of

wire 60 beyond its utility point, and the frequency of the periodic impulses placed thereon, are so proportioned that immediately beyond the utility point, the reflected wave and the succeeding wave meet and neutralize each other.

Similarly in Fig. 10 a coil spring 70 is fixedly mounted at point 71 and attached to an electromagnetic driving element 72. Attached to the spring 70 at uniform distances are horizontal wires 73 for mounting shutters, and tensioning wires 74. Upon activation of the relay 72 from an oscillator 75 a longitudinal wave of condensations and rarefactions is produced in the coil 70 which is projected therealong to the point 71 producing, as it goes along, a transverse wave in the wires 73. However, the section of the spring 70 beyond its utility point and the frequency of the impulses impressed thereon are so proportioned that the reflected wave is neutralized by the wave immediately following. These two figures, disclose, therefore, a construction for eliminating transverse and longitudinal reflections without the use of an absorbing medium. It is to be understood of course, that the wires 25 and 28 of Fig. 2 and the wires 40 and 41 of Fig. 7 may be equipped with an extension for neutralizing the reflected waves or may have the absorbing support such as section 21 in Fig. 2.

In the above description of the invention, advantage has been taken of the speed of propagation of elastic waves in highly elastic mediums such as steel and that this speed is controllable by tensioning and by the nature of the material. Furthermore, it will now be obvious that light intensification has been obtained by the use of shutters in the above manner while a commutating system has been evolved without the use of rotating heavy movable parts.

Although it is realized that many modifications of the apparatus will occur to those skilled in the art based on the principles disclosed above, these equivalent systems are intended to be within the scope of the appended claims.

What is claimed is:

1. In a system for the transmission of electrical impulses characterized by the light and shade densities of an object, a plurality of elements mounted in a rectangular pattern, means for elastically supporting said elements, means for initiating elastic waves in said last mentioned means for loosening said elements on said supports in a serial order, and means for changing the position of said elements in accordance with the strength of said impulses.

2. In a television receiving system, a plurality of similar elements mounted upon elastic supports to form a rectangular pattern, means for initiating in said elastic supports elastic waves in chronological order, a field winding and means for adjusting each of said elements to positions depending upon the strength of the currents in said field winding, said elements remaining in their adjusted positions during intervals of time when no waves are present in said elastic supports.

3. In a television transmission system for transforming electrical currents characterized by the light and shade densities of an object into proportional light intensities, the combination of a frame, a plurality of wires mounted on said frame, a plurality of movable shutters mounted adjacent one another on said wires, an elastic medium perpendicular to said wires and connected thereto, and means for initiating at one

- terminal of said medium an elastic wave perpendicular to said wires for loosening said shutters upon said wires in a serial order.
4. In a television receiving system, a quadrilateral frame, a plurality of wires uniformly placed between two opposite sections of said frame, a plurality of shutters mounted on and adapted to rotate about said wires, an elastic medium perpendicular to said wires and attached thereto, means for initiating in said elastic medium elastic waves for actuating said wires in a chronological order, a winding surrounding said frame for creating an electric field in which said shutters are positioned, a light source at one side 15 of said shutters for projecting light therethrough, and means adjacent said shutters for preventing light from passing therethrough when said shutters are in their normal positions.
5. In a television transmission system, a source 20 of light, a framework between said light and an object to be scanned, light gates mounted elastically in said screen for admitting light in a chronological order, an oscillator, means for initiating elastic waves for actuating said elements with impulses from said oscillator, and means for opening and closing said gates.
6. In a picture receiving system of the television type, a projection screen, a source of light, a framework intermediate said screen and said 25 source of light, a plurality of polygonal shaped wires connected to said framework, an elastic medium connected to said wires, an electrical unit for initiating in said wires vibrations at periodic intervals, said vibrations being initiated in said 30 wires in a serial order, a plurality of shutters having sleeve portions surrounding said polygonal wires, and a winding surrounding said frame the field of said winding adjusting the position of said shutters upon said wires when said vibrations 35 have loosened said shutters, said sleeve portions having a polygonal interior to coincide with said wires to maintain said shutters in the positions 40 to which they are adjusted by said field.
7. In a television receiving system, a plurality 45 of wires mounted in a plane at uniform intervals, a second plurality of wires mounted in another plane parallel to said first plane of wires, an elastic medium connected to said first plurality of wires, an elastic medium connected to said second plurality of wires, electrical units for initiating in said medium vibrations at different frequencies, a plurality of shutters mounted on said first plurality of wires, a second plurality of 50 shutters mounted on said second plurality of wires, said shutters being physically interconnected, and electromagnetic means for adjusting the position of said shutters on said wires when said vibrations are present simultaneously at each 55 assembly of shutters and connecting elements.
8. The method of recording television images 60 which comprises generating elastic waves, applying said waves to movable shutters in chronological order, applying a plurality of signalling impulses to said shutters, moving said shutters in accordance with the combined elastic and signalling impulse and locking the shutters in position so that the image can be reproduced at any later time.
9. The method of obtaining a permanent television 70 image which comprises generating elastic waves, applying said waves to movable shutters in chronological order, applying signalling impulses to said shutters, moving said shutters in accordance with the combined elastic and signalling impulse, locking said shutters in a per- 75 manent position and projecting a light beam therethrough.
10. In a television receiving system adapted to receive electrical impulses characterized by the light and shade densities of an object, a plurality of parallel arranged wires in the same plane 80 equally spaced from each other, a plurality of shutters on said wires, an elastic medium perpendicular to said wires, means for initiating in said elastic medium an impulse of periodic frequency in synchronism with said received impulses, means for projecting a constant intensity light beam on said shutters, and means for fastening one terminal of said elastic medium and of said wires beyond their utility point for obtaining 85 neutralization of said wave by the reflected wave from said fastening point.
11. In a system for the transmission of electrical impulses characterized by the light and shade densities of an object, means for receiving said impulses, a light source, a screen, a field winding connected to the output of said receiver, means positioned in said field intermediate said light source and said screen, said means comprising a plurality of individual light gates, and elastic 90 means for actuating said gates in a cyclic order and in synchronism with the impression of said impulses upon said field.
12. In a television system, means for generating electrical currents proportional to the light and shade intensities of unit areas of an object or image thereof means for transmitting said currents to a receiving point, elastic means at said receiving point for translating said currents into 95 spatially disposed light unit areas in accordance with said object, said means including means for generating elastic waves, a plurality of movable elements mounted on elastic supports and means for applying the elastic waves to said movable elements in a chronological order, and means for 100 retaining said light variations so disposed indefinitely.
13. In a television system, means for scanning an object or image thereof to produce electrical 105 currents proportional to the light and shade densities of unit areas thereof, means for transmitting said currents to a receiving point, a television receiving apparatus at said receiving point including a light gate having elements representing unit areas of said object scanned, and elastic 110 means for serially controlling the openings of the elements of said light gate for any period of time and for maintaining their relative positions indefinitely at any instant of reception of said currents, said means including means for 115 generating elastic waves, a plurality of movable elements mounted on elastic supports and means for applying the elastic waves to said movable elements in a chronological order.
14. In a television system, means for receiving 120 current impulses characterized by the light and shade densities of a scanned object or image, means for translating said currents into unit area light sections of a density corresponding to the unit area densities of said object, said means including means for generating elastic waves, a plurality of movable elements mounted on elastic supports and means for applying the elastic waves to said movable 125 elements in a chronological order.
15. In a television receiver, means for receiving 130 current impulses characterized by the light and shade densities of the unit areas of a scanned 135

object or image thereof, a light gate having elements representing the unit areas of the scanned object, a light source for illuminating said unit areas, and elastic means associated with said light gate for maintaining said elements in any desirable position at any instant of time for

future reproduction of said picture, said means including means for generating elastic waves, a plurality of movable elements mounted on elastic supports and means for applying the elastic waves to said movable elements in a chronological order. 80
